DESIGN FOR A COMBINATION BOTTLE OPENER AND CORKSCREW

Max Kaderli, Old Greenwich, Conn.

Application January 10, 1946, Serial No. 125,436

Term of patent 7 years

(Cl. D44—29)

To all whom it may concern:

Be it known that I, Max Kaderli, a citizen of the United States, residing at Old Greenwich, in the county of Fairfield and State of Connecticut, have invented a new, original, and ornamental Design for a Combination Bottle Opener and Cork Screw, of which the following is a specification, reference being had to the accompanying drawing, forming part thereof.

In the drawing:

Fig. 1 is a front elevational view of a combination bottle opener and cork screw illustrating my new design;

Fig. 2 is a right side elevational view of the combination bottle opener and cork screw illustrated in Fig. 1; and

Fig. 3 is a top elevational view of the combina-

tion bottle opener and cork screw illustrated in Fig. 1.

I claim:

The ornamental design for a combination bottle opener and cork screw, as shown.

MAX KADERLI.
